COOKING RANGE

Lee S. Chadwick, Shaker Heights, Marc Resek, Cleveland Heights, and William M. Day, Parma Heights, Ohio, assignors to Perfection Stove Company, Cleveland, Ohio, a corporation of Ohio

Application February 1, 1950, Serial No. 7,625

Term of patent 14 years

(Cl. D81—4)

To all whom it may concern:

Be it known that we, Lee S. Chadwick, Marc Resek, and William M. Day, citizens of the United States, residing at Shaker Heights, Cleveland Heights, and Parma Heights, in the county of Cuyahoga and State of Ohio, have invented a new, original, and ornamental Design for a Cooking Range, of which the following is a specification, reference being had to the accompanying drawing, forming part hereof.

Fig. 1 is a front perspective view of a cooking range embodying our new design; and,

Fig. 2 is a sectional view taken on line 2—2 of Fig. 1.

The side of the range, not shown, is substantially like the side shown.

The dominant features of our design reside in the portions shown in full lines.

We claim:

The ornamental design for a cooking range, as shown and described.

LEE S. CHADWICK.
MARC RESEK.
WILLIAM M. DAY.
